DEVICE, ADAPTER, TOOL, OR THE LIKE TO
FACILITATE THE MANUFACTURE OF AR-
TIFICIAL FISH LURES

Merlin M. Evans, Bethesda, Md.

Application February 6, 1937, Serial No. 124,523

7 Claims. (Cl. 43—1)

This invention relates to the manufacture of artificial fish lures of that class known as flies.

Artificial flies are made by hand. During manufacture the fibers of the hackle first applied to the hook stand out laterally all around the hook and must be held down in a clump out of the way while further work is being done, such as applying a second hackle of a different color to produce a bi-visible fly, finishing bodies, when adding tags and wings, shellacking, applying head varnish or cement, and so forth.

All the work upon the fly, and especially tying and winding of the second hackle, is rendered very difficult by reason of the workman holding the first hackle back out of the way with one hand leaving only one hand to wind the second hackle, or do other work such as tying knots and the like. Often the first hackle is mashed and crushed to such an extent as to destroy the normal regularity of distribution of the fibers around the hook and the angular inclination of the fibers to the hook. This loss of shape permits the second hackle to be unevenly exposed through large gaps in the first hackle which is undesirable, and also the mussy appearance of the finished fly is objectionable.

The present invention provides a process and apparatus whereby the hackle first applied may be conveniently held back out of the way while subsequent steps of manufacture of the fly are taking place. The workman will thus have both hands free to do all necessary work in finishing the fly and in producing uniformity in appearance not hitherto obtainable by the ordinary method of manufacture.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a perspective view showing the hackle holder and a fly, the parts of the holder being separated from each other to better illustrate the construction of the invention.

Figure 2 is a perspective view showing the holder applied to the fly ready to be moved endwise over the hackle.

Figure 3 is a perspective view showing the holder in position to hold the hackle back out of the way.

Figure 4 is a perspective view of a modified form of hackle holder in initial position on the hook.

Figure 5 is a perspective view of the form of the invention shown in Figure 4.

Figure 6 is a view similar to Figure 5 but showing a succeeding stage of assembling the parts.

Figure 7 is a perspective view of a modified form of the invention in which the diameter of one of the tubes is reduced.

Figure 8 is a perspective view of the modified form of the invention shown in Figure 7, applied endwise over the eye of the hook to hold the hackle.

Figure 9 is a perspective view of a modified form of the invention.

Figure 10 is a perspective view of another modified form of the invention having a wire slot closer.

Figure 11 is a perspective view of the hackle holder shown in Figure 13 with the slot in the tube registering with the gap in the slot closer.

Figure 12 is a perspective view of a modified form of wire slot closer.

Figure 13 is a perspective view of the tube of the hackle holder shown in Figure 14.

Figure 14 is a perspective view of another modified form of wire slot closer.

Referring now to the drawing in which like characters of reference designate similar parts in the various views, 10 designates a vise in which the hook 11 is held stationary during manufacture of the fly.

In practice the hackle 12 of a fly is applied by securing one end to the hook near the eye, a 35 waxed thread 13 being used for this purpose. The hackle is wrapped around the hook to dispose the fibers of the hackle in an outstanding position. The other end of the hackle is then tied to the hook and the thread may be then 40 placed in a spring clip 14 so as to be ready for the application of a second hackle, or tag, body, wings, or the like.

During all subsequent steps of manufacture, the first hackle 12 must be held out of the way 45 and to accomplish this purpose, one form of the invention provides a hackle holder comprising a pair of tubes 15 and 16, one of which is telescopically received within the other. Each tube has a longitudinal slot 17 and the slots of both 50 tubes may be brought into registration so that the tubes, telescoped together, can be applied laterally to the thread 13 and the hook 11. After the thread and hook have passed through the registering slots into the interior of the tube, the 55

tubes may be rotated relatively to each other to dispose the slots out of registration so that the tubes form a continuous annulus around the thread and the hook as shown in Figure 2.

5 The tubes may now be moved as a unit toward and over the hackle to deform the fibers thereof and press them down in a longitudinal bundle extending substantially in the direction of length of the hook, as shown in Figure 3. The fibers 10 thus confined by the holder are out of the way of the operator's hands while subsequent steps of manufacture are being performed, as for example, applying a second hackle of a contrasting color to produce a bi-visible fly. The second 15 hackle 18 is applied back of the first hackle by wrapping the hackle around the hook and tying the same securely in the same manner as the first hackle. If no further work is to be done upon the fly, the holder may now be detached 20 by backing the same off the bundled first hackle 12 and rotating the tubes relatively to each other until the slots therein register whereupon the holder may be withdrawn laterally from the thread.

25 When the holder is removed the fibers of the first hackle instantly spring back to their normal outstanding position, and return to normal regularity of distribution around the hook and to normal angular inclination with respect to the 30 hook. Thus the second hackle will be exposed through the first hackle uniformly when viewed from the direction of the eye of the hook. In use it will be found that the fly thus manufactured will retain its formation and appearance 35 permanently since there are no mashed places in the first hackle to flatten out and bog down as is usually the case.

The holder may be formed of any light strong 40 material such as metal, Celluloid, paper, or other material.

Figures 4, 5, and 6 illustrate a modified form of the invention. The holder in this instance comprises interfitting tubes 19 and 20, one of the tubes having a slot 21 to permit the tube being passed laterally on to the hook 11. The other tube is formed of resilient material and is provided with a wide gap or slot 22 to receive a portion of the side of the tube at the slot of the latter, as shown in Figure 5, and permit the tube 20 50 being sprung or snapped on to the tube 19, as shown in Figure 6, when the latter is applied to the hook, as shown in Figure 4.

Another modified form of the invention is shown in Figures 7 and 8. In this form of the 55 invention the hackle holder comprises a pair of tubes 23 and 24 each having respective slots 25 and 26. The tube 23 is provided with a flanged end wall 27 which is provided with an axial orifice 28 for the purpose of reducing the diameter 60 of the tube at one end. The application of this holder to the hackle to bundle the hackle may be made in the same manner as above described in connection with the holder shown in Figure 1, or if desired, the tubes may be first telescoped together and then applied over the eye of the hook to bundle the hackle toward the bend in the hook. Of course, the form of the invention shown in Figure 1 may be applied over the eye of the hook also when desired. By thus applying the holder 70 shellacking may be conveniently done near the eye of the hook. In Figure 9 there is shown another modified form of the invention, the hackle holder comprising a pair of slotted tubes 29 and 30 substantially duplicates of the above described 75 tubes 15 and 16 with the exception that the tube

29 is provided at one end with a grip 31 which promotes easy manipulation of the holder.

In the modified form of the invention shown in Figure 10 the tube 40 is provided with a longitudinal slot 41 and also is provided with a circumferential groove 42 which is indented or pressed into the tube and terminates at the slot, as best shown in Figure 13.

A wire slot closer 43 is mounted to rotate in the groove, the slot closer preferably being 10 formed of a ring having a gap 44 in one side, as shown in Figure 11, adapted to be brought into and out of registration with the slot in the tube. A grip 45, produced by deforming the ring, 15 may be readily grasped for manipulating the slot closer. The grip lies wholly in the plane of the ring so as to be out of the way during winding or tying of a hackle or performing other work on the fly.

By again referring to Figure 10 it will be seen 20 that the hackle has been wound on the hook by means of conventional pliers 46 used in this type of work, and is ready to be tied at the front. At this point the hackle holder, with the parts in the position shown in Figure 11, may be applied to 25 the thread and slipped over the eye of the hook then moved rearwardly to bunch the fibers of the hackle. Thereupon the slot closer 43 may be rotated to bridge the slot in the tube, as illustrated. In this position of the parts there is 30 plenty of room left between the holder and the eye of the hook to permit the easy and accurate tying of the quill end of the hackle to the hook. After the hackle has been applied the tube may be backed off from the hook and thereupon the 35 gap in the slot closer may be brought into registration with the slot in the tube to permit the device being disengaged from the hook and thread.

In the modified form of slot closer shown in 40 Figure 12 the wire ring 47 has the gap 48 disposed diametrically opposite the grip 49 instead of in the side of the ring, as shown in Figure 11. This relative position of the gap and grip permits the device to be quickly applied from 45 directly above or below the thread.

In the modified form of slot closer shown in Figure 14, the wire ring 50 has the gap 51 located at the single wire grip 52 and this construction is advantageous from the standpoint of simplicity 50 since it is merely a hook.

From the above description it is thought that the construction and operation of the invention will be fully understood without further explanation.

55

What is claimed is:

1. A holder for receiving the tying thread and the hackle of a fish lure during manufacture of the lure, comprising a slotted tube adapted to be disposed with its slot in position to permit application of the tube laterally to the tying thread and hackle of the lure, and means for closing the slot to permit the tube forming an annulus around the hackle and thread, the tube being of sufficient diameter to deform the outstanding fibers of the hackle to a position substantially in the direction of length of the lure.

2. A holder for confining fish lure hackles out of the way during the making of the lure, comprising interfitting slotted tubes adapted to be 70 disposed with their slots in registration to permit application of the tubes laterally to the lure, the tubes being relatively rotatable to dispose the slots out of registration and permit of the tubes being moved as a unitary annulus upon the lure 75

to engage and press back the fibers of the hackle from outstanding position to a position substantially in the direction of length of the lure.

3. A holder for confining fish lure hackles out of the way during the making of the lure, comprising a slotted tube, and a resilient tube adapted to be snapped on to the slotted tube to close the slot thereof, the slotted tube being of sufficient diameter to engage the hackles of the lure and 10 press them back from outstanding position to a position substantially in the direction of the length of the lure.

4. A holder for confining fish lure hackles out of the way during the making of the lure, comprising a resilient tube having a normally closed 15 longitudinal slot, and means on the tube for opening the slot to permit the application of the tube laterally to the lure, the tube being adapted to be slid toward and over the hackle to press back 20 the fibers and confine them in a bundle out of the way.

5. A holder for confining fish lure hackles out of the way during the making of the lure comprising, a tube having a longitudinal slot, and a curved wire mounted to rotate on the tube to bridge the slot in the tube.

6. A holder for confining fish lure hackles out of the way during the making of the lure comprising, a tube having a longitudinal slot and having a circumferential groove terminating at the slot, and a split wire ring in the groove adapted to be rotated on the tube to bridge the slot.

7. A holder for confining fish lure hackles out of the way during the making of the lure comprising, a tube having a longitudinal slot, a wire ring on the tube having a gap, and a grip on 15 the ring by which the ring may be rotated on the tube to bring the gap into and out of registration with the slot in the tube.
